UNITED STATES PATENT OFFICE.

JOHN KILSHAW, OF ST. PAUL, MINNESOTA.

HEATING-STOVE.

SPECIFICATION forming part of Letters Patent No. 273,106, dated February 27, 1883.

Application filed December 8, 1882. (Model.)

To all whom it may concern:

Be it known that I, JOHN KILSHAW, of St. Paul, in the county of Ramsey and State of Minnesota, have invented a new and useful 5 Improvement in Heating-Stoves, of which the following is a full, clear, and exact description.

The invention relates to the hollow side-perforated cone, which has been used to admit air laterally to the center of fire and into the 10 combustion-chamber above the fire, so that a more perfect combustion may take place in all parts of the fire. The air which is admitted has been so warmed by its contact with the inner surface of the cone that it more readily 15 supports combustion in the gases and but little is carried up by the draft before its oxygen has been utilized.

The object of my invention is to increase the heating-surface which comes in contact with 20 the fire and that which contacts with and supplies heat to the air as it ascends on the inside of the cone.

Reference is to be had to the accompanying drawings, forming part of this specification, in 25 which similar letters of reference indicate corresponding parts in all the figures.

Figure 1 is a side elevation of a stove provided with my improved fuel-economizing cone arranged in it as I propose. Fig. 2 is a perspective side elevation of my improved fuel-saving cone, and Fig. 3 is a sectional elevation of the cone.

I make a hollow fluted and perforated cone, 30 a, of cast-iron, fire-clay, or any other approved

refractory material, and arrange it in the fire-pot b, of a stove, as indicated by the dotted lines in Fig. 1, locating it in the center of the grate, and fastening it by pins or bolts inserted in flanges d, of the base, and passing through the grate in any way. By the fluted 35 form of the shell of the cone larger area is afforded for the cooling effect of the air for the protection of the substance of the cone from the effect of the heat than is afforded by the plain form. The perforations e allow the air rising 40 up in the cone to flow through it into the fire for the protection of the cone and the promotion of combustion. It is believed that with a cone of this kind a considerable saving of fuel may be effected in the production of a 45 given amount of heat. While I prefer to make the cone fluted, it may be used in plain form 50 with good results.

What I claim as new and of my invention is—

A hollow side-perforated cone fluted on the inside and outside to increase the contact-surface for the air which enters the inside and the fuel which bears upon the outside, whereby the air which is fed to the inside of the fire 55 and to the products of combustion may be more thoroughly and more rapidly heated, as described.

JOHN KILSHAW.
